UNITED STATES PATENT OFFICE.

JOHN HENRY DEVLIN, OF PARIS, FRANCE.

FINGER-NAIL POLISHER.

1,247,089.

Specification of Letters Patent. Patented Nov. 20, 1917.

Application filed November 9, 1914. Serial No. 871,179.

To all whom it may concern:

Be it known that I, JOHN HENRY DEVLIN, a citizen of the United States of America, residing at Paris, France, have invented a new 5 and useful Improved Finger-Nail Polisher, of which the following is a specification.

The present invention relates to an improved device allowing the finger nails to be polished with great ease and remarkably 10 efficiently. The device adjusts itself in a perfect manner to the shape, curvature and convexity of the finger nail and enables all parts of the nails to be reached without the least difficulty. Devices for polishing the 15 finger nails known hitherto have a polishing surface very hard, without any give, in such a way that in order to operate upon the whole convex surface of the nails, it is necessary to rub the latter for a very long time 20 and to constantly vary the inclination of the instrument. When the operation is carried out quickly only the middle top portion, which is the most convex, of the nail, is polished, while the lateral portions remain dull, 25 and this gives a careless and disagreeable appearance to the nails. Some finger nails have a curvature which is hardly at all regular, presenting reëntrant parts and other parts which project more. With known instruments these finger nails can only be polished with very great difficulty.

The present invention is intended to remove these inconveniences and to provide an arrangement allowing the nails to be 35 polished with the greatest ease and in a perfect manner. The device consists essentially in applying skin or other material intended to form a rubbing surface upon a pneumatic chamber inflated in such a manner as to 40 stretch the skin and to give it a certain resistance, while still assuring that it remains quite supple. This pneumatic device adjusts itself and applies itself to the finger nails in a very exact manner and shapes 45 itself to all the shapes and all the curvatures of the latter in such a manner that it is only necessary to rub for a few moments in order to instantly polish the whole surface of the finger nails.

50 The annexed drawing shows by way of example, several methods of carrying this invention into practice.

Figure 1 is an elevation of my invention complete with outer cover and inflation valve.

55

Fig. 2 is a cross section of Fig. 1.

Fig. 3 is a cross section of a modification.

The device comprises essentially an exterior envelop 1 of chamois skin or other 60 suitable material, which is preferably given a cylindrical shape, shown in Fig. 1, by stitching or by other means. An air chamber or a bladder of india rubber 2 similar to those of pneumatic bandages or of toy 65 balloons, is arranged in the interior of this envelop 1. This chamber or bladder is inflated in the usual well known manner, preferably by means of a small air pump, the connection of which is screwed on to the 70 valve 3. By compressing air in the interior of the chamber or bladder 2 the exterior skin is inflated to the desired extent.

In order to prevent the skin 1 from sliding over the chamber or bladder 2 during 75 polishing the finger nail, swellings or ribs may be formed on the interior surface of the skin 1 for maintaining the chamber or bladder 2 in position.

In order to give the arrangement a certain rigidity in the longitudinal direction it may be divided internally by a partition 5 of flexible metal, leather, and so forth (Fig. 2.) In this case there is an air chamber or bladder 2 upon each side of this partition. The two chambers or bladders can be connected at one of the ends and be connected to a common valve.

The same rigidity can also be obtained by means of a frame of metallic wire or other 90 material 6, preferably having a section of an inverted channel (Fig. 3). It should be understood that other shapes and other methods of construction may be employed. The details of construction can even be 95 modified. Moreover, the different constituent elements of this invention can be replaced by others playing the same part and giving the same result.

What I claim is:—

100 A flexible hand-polisher for treating the finger-nails, capable of being folded, of inflation and deflation, and of being rolled up for packing, comprising in combination an

outer envelop presenting polishing surfaces, an impervious air chamber, a valve controlling an opening to said air chamber and adapted for the inflation and deflation thereof and internal means for imparting longitudinal stiffness to the apparatus.

5 In testimony whereof I sign my name to

this specification in the presence of two subscribing witnesses.

JOHN HENRY DEVLIN.
